INERTIA TRIP FOR CIRCUIT BREAKERS

Lloyd W. Dyer, Pittsburgh, Pa., assignor to Westinghouse Electric Corporation, East Pittsburgh, Pa., a corporation of Pennsylvania

Application January 13, 1945, Serial No. 572,597

7 Claims. (Cl. 200—52)

1

This invention relates generally to electric circuit breakers, and more particularly to high speed circuit breaker operating and trip mechanisms.

It sometimes happens that in closing a circuit breaker against a short circuit, the magnetic forces encountered as soon as the arcing tips touch are high enough to prevent complete closing of the main breaker contacts, and consequently the breaker may be damaged due to excessive arcing. Of course, relays may be employed which will trip the breaker when the breaker is closed on a fault, but these are too slow in operation to afford adequate protection against excessive arcing in the event the breaker stalls during a circuit closing operation.

In the copending application of Alfred Loos, Serial No. 470,939, Circuit breakers, filed December 31, 1942, now abandoned, and assigned to the same assignee as this invention, there is disclosed a means for tripping the breaker in the event the breaker stalls during circuit closing operation for any reason, but the tripping means of Loos is operated by reverse movement of the breaker.

It is, therefore, one object of this invention to provide novel means for instantaneously tripping the breaker free of its operating mechanism in the event the breaker suddenly stops or stalls during a circuit closing operation.

A more specific object of this invention is to provide inertia means which is responsive to the sudden stopping or stalling of a circuit breaker during its circuit closing movement, to instantaneously trip said breaker free of its operating mechanism.

These and other objects of this invention will become more apparent upon consideration of the following detailed description of a preferred embodiment thereof, when taken in connection with the attached drawing, in which:

Figure 1 is a diagrammatic view of a circuit breaker and circuit breaker operating mechanism embodying this invention, with a control circuit for the mechanism illustrated diagrammatically;

Fig. 2 is an enlarged side elevation view of a part of the mechanism illustrated in Fig. 1, but at a different position; and

Fig. 3 is a side elevation view of the mechanism parts illustrated in Fig. 2, but at a different position.

The circuit breaker illustrated on the drawing is provided with stationary contacts 2 adapted to be bridged by a movable bridging contact structure 4. Stationary contacts 2 include main contact portions 6 adapted to be engaged by a main bridging contact bar 8. Stationary contacts 2

2

also include angularly extending arcing contact portions 10 adapted to be engaged by a resilient bridging member 12, preferably comprising a laminated member made up of a plurality of leaf springs.

In the closed circuit position shown in full lines in Fig. 1, bridging member 12 for the arcing contact portions 10 is in substantially straightened condition. However, bridging member 12 normally assumes the curved position shown in dotted lines in Fig. 1, so that when bridging structure 4 is moved away from stationary contacts 2, main bridging contact 8 will disengage main contact portion 6 while bridging member 12 remains engaged with arcing contact portions 10, so that the arc will be drawn between bridging member 12 and arcing contact portions 10. In closing the breaker, bridging member 12 will engage arcing contact portions 10 before main bridging contact 8 engages main contact portion 6.

Bridging contact structure 4 is mounted on the lower end of a lift rod 14, and the lift rod is biased downwardly in a direction to open the circuit by a coil spring 16, which reacts between a shoulder 20 provided on the lift rod, and a stationary frame member 18. Unless bridging contact structure 4 is held by other means at the closed circuit position, it is apparent that spring 16 will maintain bridging contact structure 4 at an open circuit position.

Lift rod 14 is adapted to be actuated by an operating lever 22 pivotally connected therewith as at 24. Operating lever 22 is pivotally mounted intermediate its ends as at 26 on a stationary frame member 27, and is pivotally connected at its other end with an operating rod 30, as by a pivot pin 28.

Operating rod 30 is adapted to be connected with a motive means for closing the breaker contacts by a trip-free mechanism, such for example, as the trip-free mechanism disclosed in the copending application of J. M. Cumming et al. on Circuit breakers, Serial No. 437,669, filed April 4, 1942, now Patent No. 2,403,082, issued July 2, 1946, and assigned to the same assignee as this invention. Such a trip-free mechanism comprises, in general, a trip-free lever 32 which is pivotally connected with operating rod 30 intermediate the ends of the lever as by a pivot pin 31. Trip-free lever 32 is pivotally connected at one end, as by a pivot pin 34, with an actuating lever 36 adjacent one end of the latter, and the actuating lever is adapted to be pivotally supported at its opposite end by a pivot pin 38. Actuating lever 36 is biased for movement about its supporting pivot

38 in a clockwise direction as viewed in Fig. 1, by a coil compression spring 39. Actuating lever 36 is, however, normally prevented from rotating under the influence of biasing spring 39, by engagement of pivot pin 34 thereof by a latch lever 40 pivotally mounted on a stationary frame member by means of a pivot pin 42. Trip-free lever 32 carries a latch pin 43, which, in the normal position of the parts as shown in Fig. 1, is substantially in alignment with pivot pin 38, and is adapted at this position to be held by a latch lever 44 pivotally mounted on a stationary frame member as by a pivot pin 46. The trip-free lever 32 is provided at its other end with a latch release projection 47 adjacent to, but spaced from, pivot 34, for a purpose to be hereinafter described. Actuating lever 36 is adapted to be connected with a motive means 50 by means of a connecting rod 48 pivotally connected to the actuating lever as at 52. Motive means 50 may be of any desired type, such for example as a solenoid having a core attached to connecting rod 48, or it may be a fluid motor having a piston attached to connecting rod 48.

With the parts in the positions shown in Fig. 1, it is apparent that bridging contact structure 4 of the circuit breaker is held latched in its closed circuit position by latches 40 and 44. In order to permit the breaker to be opened by spring 16, there is provided an integral extension 54 on latch lever 44 which is adapted to be engaged by a solenoid plunger 56, when its trip-coil 53 is energized. Trip coil 58 is shown as connected in a control circuit which may be energized by any suitable means, such for example as a battery 69, and the control circuit has a pair of normally open contacts 62. A solenoid plunger 64 carries a bridging contact for bridging contacts 62 of the control circuit when its operating coil 66 is energized. Coil 66, in the embodiment of the invention illustrated, is adapted to be energized by a current transformer 68 associated with the circuit 70 in which the circuit breaker contacts are connected.

When currents such as overload currents are present in circuit 70 in excess of a predetermined value, solenoid coil 66 will be energized sufficiently to attract plunger 64 and close the control circuit by bridging its contacts 62. This energizes trip-coil 58, causing its plunger 56 to move upwardly and engage latch extension 54, to release latch lever 44 from pin 43 on trip-free lever 32. This not only releases bridging contact structure 4 of the breaker for rapid movement to open circuit position by spring 16, but also disconnects the moving contact structure from motive means 50, since trip-free lever 32 is free to move independently of actuating lever 36 to the position shown in Fig. 3. During the last part of opening movement of trip-free lever 32, latch release projection 47 thereon is adapted to engage and move latch lever 40 to release pivot pin 34, and thus permit spring 39 to move actuating lever 36 in a clockwise direction about its pivot 38 as viewed in Fig. 1. Such clockwise rotation of actuating lever 36 raises connecting rod 48 and pivot pin 34 connecting the actuating lever to trip-free lever 32, and accordingly rotates trip-free lever 32 in a clockwise direction with respect to its pivot 31 on operating rod 30. This resetting movement of trip-free lever 32 and actuating lever 36 caused by spring 39, continues until the parts attain the position shown in Fig. 2 of the drawing, where latch pin 43 of the trip-free lever will be reengaged by latch lever 44.

With the parts in the position shown in Fig. 2,

it will be observed that motive means 50 is now operatively connected with operating rod 30, so that the motive means may be energized to pull connecting rod 48 downwardly and reclose the circuit breaker. Reclosing movement of the breaker continues until pivot pin 34 connecting trip-free lever 32 and actuating lever 36 is reengaged by latch lever 40, which is the position of the parts illustrated in full-lines in Fig. 1.

As previously pointed out, it sometimes happens that when the circuit breaker is closed against a short circuit or similar heavy overload, the magnetic forces encountered when bridging contact 12 first touches arcing contact portions 10, resist closing of the contacts, and if of sufficient magnitude may stall the breaker as soon as bridging contact 12 engages arcing contact portions 10. In order to prevent undue damage to the breaker in the event of the occurrence of such a condition, means is provided to open the breaker as fast as possible, comprising an inertia weight 72 which is pivotally mounted as at 71 on a lever 73 pivotally connected with operating rod 30 as at 74. Lever 73 is pivotally mounted intermediate its ends on a stationary member 75. Pivotal movement of inertia weight 72 with respect to lever 73 is limited by the spaced stop 76 provided on the lever. Inertia weight 72 is provided with an operating projection 78 which extends into proximity with the long leg 80 of a generally U-shaped actuator lever pivotally mounted on a stationary frame member as at 82. The short leg 84 of the U-shaped actuating lever is adapted to be connected with latch lever 44, by means of a pivoted connecting link 86.

It will be observed that in the closed position of the circuit breaker illustrated in full lines in Fig. 1, operating projection 78 of inertia weight 72 cannot engage leg 80 of the actuator lever 44 upon pivotal movement of the inertia weight on pivot 74. When latch 44 is released by trip coil 58 or other means to effect a circuit opening operation of the breaker, leg 80 of the actuator lever will be moved away from the path of movement of operating projection 78 of the inertia weight. However, when the breaker is closed, the long leg 80 of the actuator lever will occupy the position shown in Fig. 1 closely adjacent the path of movement of operating projection 78 of the inertia weight, so that if the breaker is stopped suddenly, or the rate of movement thereof suddenly decreases, for example, when the arcing contacts touch, or even before in the event of failure of the closing means, inertia weight 72 will tend to continue its movement at the same rate and as a result will rotate in a clockwise direction about its pivot 71 so that operating projection 78 thereof will engage the long leg 80 of the actuator lever and cause it to release latch lever 44, and thus permit breaker opening spring 16 to open the breaker at a rapid rate, since release of latch lever 44 also releases the bridging contact structure 4 from motive means 50. It will now be apparent that the operating projection 78 of the inertia weight occupies a position where it clears long leg 80 of the actuator lever when the circuit breaker is at its fully closed position (Fig. 1), because the parts come to a sudden halt at this position and it is not desired that the inertia weight 72 be effective to open the breaker at the fully closed position. However, it is apparent that the inertia weight 72 is effective whenever rotation thereof occurs relative to operating rod 30 during the circuit closing movement at any position of the breaker contacts except the fully

closed position, to engage the long leg 80 of the actuator lever to cause release of latch 44, and thereby permit rapid opening of the breaker contacts.

From the foregoing, it is apparent that this invention provides a means for effecting as rapid an opening of the breaker contacts as possible whenever the contacts stall or hesitate in movement during a circuit closing operation. This may be due to excessive magnetic forces encountered or to failure of the operating mechanism, as previously pointed out, but in any event, it is essential that rapid opening of the breaker occur as soon as possible in order to prevent undue damage to the breaker.

Having disclosed a preferred embodiment of the invention in accordance with the patent statutes, it is desired that this invention be not limited to this particular structure, inasmuch as it will be apparent, particularly to persons skilled in the art, that many modifications and changes may be made in this particular construction without departing from the broad spirit and scope of this invention. It is, therefore, desired that this invention be interpreted as broadly as possible, and that it be limited only as required by the prior art.

I claim as my invention:

1. In a circuit breaker, a circuit interrupter, means operable to initiate actuation of said interrupter to an open circuit position, operating means operable to initiate closing of said interrupter, and inertia means mounted on a part of the interrupter which moves at least during a circuit closing operation thereof so as to be operative solely in response to the occurrence of a predetermined decrease in the rate of movement of said interrupter in the circuit closing direction during a circuit closing operation before full closed circuit position is reached, to automatically cause said opening means to open said interrupter.

2. In a circuit breaker, a circuit interrupter, means for initiating actuation of said interrupter to an open circuit position, operating means operable to initiate closing of said interrupter, an inertia weight mounted for limited relative movement on a part movable with said interrupter at least during circuit closing movement, and means operated by relative movement of said weight caused by a predetermined decrease in the rate of movement of said interrupter during a circuit closing operation before full closed circuit position is reached, to automatically cause said actuating means to open said interrupter.

3. In a circuit breaker, circuit interrupting means biased to an open circuit position, operating means operable to close said interrupter, means releasably coupling said operating means to said interrupter, inertia means mounted on a part of the interrupter which moves at least during a circuit closing operation thereof so as to be operative solely in response to the occurrence of a predetermined decrease in the rate of movement of said interrupter in the circuit closing direction during a circuit closing operation before full closed circuit position is reached, to automatically effect release of said coupling to permit rapid opening of said interrupter.

4. In a circuit interrupter, relatively stationary and movable contact means, operating means for initiating movement of said movable contact

means into engagement with said stationary contact means to close the circuit, means for initiating movement of said movable contact means away from said stationary contact means to open the circuit, and inertia means mounted on a part movable with said movable contact means at least during a circuit closing operation so as to be operative solely in response to the occurrence of a predetermined decrease in the rate of movement of said interrupter in the circuit closing direction during a circuit closing operation before full closed circuit position is reached to automatically cause said circuit opening means to open said interrupter.

5. In a circuit interrupter, relatively stationary and movable contact means, operating means for initiating movement of said movable contact means into engagement with said stationary contact means to close the circuit, means for initiating movement of said movable contact means away from said stationary contact means to open the circuit, an inertia weight mounted for limited relative movement on a part movable with said movable contact means at least during circuit closing movement, and means positioned adjacent the path of movement of a member movable with said weight, except for a small portion of said path of movement at and closely adjacent closed circuit position, so as to be engaged by said member upon relative movement of said weight caused by a predetermined decrease in the rate of movement of said interrupter during a circuit closing operation before full closed circuit position is reached to automatically cause said circuit opening means to open said interrupter.

6. In a circuit breaker, a circuit interrupter, operating means operable to open and close said interrupter, and inertia means mounted on a part of the interrupter which moves at least during a circuit closing operation thereof so as to be operative solely in response to the occurrence of a predetermined decrease in the rate of movement of said interrupter in the circuit closing direction during a circuit closing operation before full closed circuit position is reached, to automatically cause said operating means to open said interrupter.

7. In a circuit breaker, a circuit interrupter, operating means operable to open and close said interrupter, an inertia weight mounted for limited relative movement on a part movable with said interrupter at least during a circuit closing operation, and means operated by relative movement of said weight caused by a predetermined decrease in the rate of movement of said interrupter during a circuit closing operation before full closed circuit position is reached, to automatically cause said operating means to open said interrupter.
